5,082,261 1/1992 Pelfry ..... 273/1.5 R

[75] Inventor: John J. Driska, Princeton Junction, N.J.

Primary Examiner—Melvin B. Feifer
Attorney, Agent, or Firm—Amster, Rothstein & Ebenstein

[73] Assignee: Azrak-Hamway International Inc., New York, N.Y.

[57] **CLAIM**

[**] Term: 14 Years

The ornamental design for a basketball basket and backboard assembly, as shown and described.

[21] Appl. No.: 716,376

DESCRIPTION

[22] Filed: Jun. 14, 1991

FIG. 1 is a front elevational view of a basketball basket and backboard assembly showing my new design, with a stand therefor being indicated in phantom line; FIG. 2 is a side elevational view thereof; FIG. 3 is a rear elevational view thereof; FIG. 4 is a top plan view thereof; FIG. 5 is a bottom plan view thereof; and, FIG. 6 is a side elevational view, similar to FIG. 2, but showing the assembly in a position of use, with a basketball being indicated in phantom line.

Related U.S. Application Data

The phantom lines are for illustrative purposes only and form no part of my design.

[63] Continuation-in-part of Ser. No. 651,737, Feb. 7, 1991, Pat. No. 5,066,006.
